Int. Cl. D23—03

U.S. Cl. D23—127

FIG. 1

FIG. 2

FIG. 5

FIG. 3

FIG. 4

FIG. 1 is a perspective view of a dinnerware firing rack showing my new design;

FIG. 2 is a top plan view thereof;

FIG. 3 is a front elevation view thereof;

FIG. 4 is a side elevation view thereof; and

FIG. 5 is a perspective view of the base member, the remaining portions thereof being omitted for clarity of illustration.

The bottom of the firing rack is substantially flat and unornamented and the three upright support posts are identical to each other.

I claim:

The ornamental design for a dinnerware firing rack, as shown and described.
